UNITED STATES PATENT OFFICE

CHARLES E. CARPENTER, OF CHICAGO, ILLINOIS

DRAFT APPLIANCE AND THE LIKE

Application filed September 7, 1928. Serial No. 304,464.

This invention has to do with certain improvements in draft rigging for railway cars and the like. The invention has to do with the construction of the draft rigging as a whole; but it has reference particularly to improvements in the means for buffering and taking up the recoil and shock incident thereto.

The invention has reference, among other things, to improvements in the friction creating devices whereby the energy of the recoil is dissipated in the form of friction, with consequent generation of heat. This heat is, of course, promptly dissipated into the surrounding parts and the atmosphere.

One object of the invention is to provide a friction device which will be very effective in its function and which will be capable of promptly dissipating a large amount of energy within a relatively small space.

In connection with the foregoing, a further object is to provide an arrangement whereby the friction will be steadily increased as the amount of movement of the coupler increases, thereby producing an increased resistance to further coupler movement. This will also assist in bringing about a rapid dissipation of the energy of the recoil.

30 A further object of the invention is to provide an arrangement such that a very smooth and effective operation will be insured, thus still further eliminating unnecessary shock and providing a more satisfactory operation.

35 Another object of the invention is to provide a draft rigging construction of simple form and one which can be manufactured relatively cheaply and at the same time built into a very rugged and substantial form of structure.

40 Other objects and uses of the invention will appear from a detailed description of the same, which consists in the features of construction and combinations of parts herein-after described and claimed.

In the drawings,—

Fig. 1 shows a horizontal plan view of a draft rigging embodying the features of the 45 present invention, the side bars of the car

frame and certain other structures being shown in section;

Fig. 2 shows a cross section substantially on the line 2—2 of Fig. 1, looking in the direction of the arrows, the coupler being 55 shown in elevation;

Fig. 3 shows a fragmentary side elevation on the line 3—3 of Fig. 1, looking in the direction of the arrows;

Figs. 4, 5, 6, 7, 8 and 9 show other fragmentary side elevations similar to that of Fig. 3, but illustrating modified types of construction; and

Fig. 10 shows a fragmentary horizontal section through still another modified form 65 of construction in which use is made of a friction block of spherical, segmental form.

Referring first to Figs. 1 and 2, I have illustrated the draft rigging as being incorporated between a pair of frame side-bars 12 70 and 13 of the car frame. These frame bars are of the usual construction with the exception that they are slotted to accommodate certain of the moving parts of the draft rigging, as will be presently explained.

The frame bars 12 and 13 are preferably boxed by top and bottom plates 14 and 15 throughout their length in that portion wherein the draft rigging is accommodated. In this way the frame bars 12 and 13, together with the cover plates 14 and 15, establish a longitudinally extending, rectangular chamber within which the draft rigging is accommodated.

The foregoing chamber is closed at its inner or rear end by a fixed block 16 preferably in the form of a casting having an encircling flange 17 which seats within the housing aforesaid. This flange is riveted to the plates 12 and 13 and also to the cover plates 14 and 15 by the rivets 18, so that it establishes a very rigid abutment.

The other end of this housing is partially enclosed by a casting 19 which has the inner end wall 20 and the encircling flange 21. 95 This casting preferably projects somewhat beyond the end of the car frame, where it is provided with a flange 22.

The end wall 20 of the casting 19 establishes an abutment at that end of the hous- 100

ing wherein the draft rigging is accommodated. This abutment is provided with an opening 23 of sufficient size to accommodate the stem 24 of the coupling 25, which coupling is of any convenient form, such as a Gould 5 coupler.

Within the housing and between the abutments 16 and 20 there is placed a heavy yoke 26, preferably of rectangular form and in the form of a casting. At its front end this yoke 10 is provided with a pair of projections or bifurcations 27 and 28 establishing between them a space for the accommodation of the stem 24. Said stem is connected to the lugs 27 and 28 by the pin 29, the arrangement being such as to allow for the necessary amount 15 of rocking movement of the coupler while at the same time communicating the push and pull forces to the yoke 26.

The yoke 26 surrounds a box which includes 20 a pair of end walls 30 and 31 and a pair of side plates 32 and 33. The side plates are set between the edge portions of the end walls and serve to keep them properly spaced apart.

The side plates 32 and 33 are provided with 25 friction face flanges 34 and 35 which press against the inner faces of the side plates 12 and 13. Furthermore, these side plates 32 and 33 are free to move towards and from each other a slight amount (being disconnected from the end plates 30 and 31).

There are transversely extending springs 36, 37, 38 and 39 between the opposite corners of the side plates 32 and 33, said springs 35 serving to press said side plates firmly against the friction plates 34 and 35 (or against the side plates 12 and 13 in case the plates 34 and 35 are integral with the side plates 32 and 33). Ordinarily the friction plates 34 and 35 will 40 be formed integrally with the side plates 32 and 33 and will travel therewith, so that the friction will be created between the plates 34 and 35 and the plates 12 and 13, respectively.

45 There is a cross pin 40 the central portion of which extends across the box already referred to, and the end portions of this pin extend through holes in the side plates 32 and 33 (and the friction plates 34 and 35). These 50 holes are just of sufficient size to accommodate the pin, so that as the box moves back and forth under the impulse of the yoke 26 the pin 40 also travels back and forth with it.

55 The end portions 41 and 42 of this pin project through slots in the frame-bar plates 12 and 13 so that the pin may move back and forth the necessary distance with respect 60 to the frame of the car itself. The end portions of these slots are defined by the dotted lines 43, 44, 45 and 46 (see Fig. 1).

Mounted on the projecting ends 41 and 42 of this pin are the wedge blocks 47 and 48, 65 respectively. In the construction illustrated

in Figs. 1, 2 and 3, these wedge blocks are provided with tapered ends.

The wedge blocks 47 and 48 work within tapered sockets of the abutment blocks 49 and 50, said abutment blocks being rigidly 70 secured to the outside faces of the frame bars 12 and 13. These abutment blocks are provided with central friction socket receptacles within which the blocks 47 and 48 are accommodated, said receptacles being provided 75 with the companion tapering friction surfaces 51 and 52, as best shown in Fig. 3.

The blocks 49 and 50 are also centrally slotted to accommodate the end portions of 80 the pin 40 so as to allow for the necessary back and forth movement thereof. The blocks 47 and 48 are provided with holes of only sufficient size to accommodate the end portions of the pin, so that these blocks 85 are compelled to travel back and forth with the pin.

Due to the above construction, it follows 90 that as the yoke is moved back and forth it carries with it the plates 32 and 33, and these in turn carry the pin 40 on which are mounted the blocks 47 and 48. Consequently the blocks 47 and 48 are compelled to ride on the tapered surfaces of the blocks 49 and 50. The blocks 47 and 48 have a sufficient bearing 95 on the pin 50 to prevent said blocks from tilting and biting into and binding on the pin.

The end portions 41 and 42 of the pin 40 carry the end blocks 53 and 54, and the compression springs 55 and 56 are placed on the 100 pin between the blocks 47 and 48 and the end blocks 53 and 54, respectively. These compression springs serve to force the blocks 47 and 48 against the companion friction surfaces so that in either direction of movement a very large amount of friction will 105 be generated, resulting in a tendency to check the rebound and also to waste the energy of the recoil in the form of heat. This friction is entirely supplemental to the friction between the box and the side plates 12 and 13, since that friction is dependent upon the springs 36, 37, 38 and 39.

The pin 40 is preferably provided with 110 shoulders 57 and 58 which bear against the inside faces of the plates 32 and 33. These shoulders thus serve as abutments against which the plates 32 and 33 may come to rest under the influence of the springs 55 and 56.

The box is normally restored to its central 115 position and the draw-bar forces are normally taken up by the sets of end springs 59 and 60 indicated in Figs. 1 and 2. The springs 59 (preferably four in number) are placed between the box end-wall 30 and the abutment 20; and the springs 60 (preferably 120 four in number) are placed between the box end-wall 31 and the abutment 16. Preferably also said end walls and abutments are 125 provided with lugs or central pins by means 130

of which the springs are kept in proper alignment and held in place.

These groups of springs 59 and 60 are preferably of sufficient strength and characteristics to take up the full amount of draw-bar force necessary without bringing the yoke and box to a dead standstill except under exceptional conditions. Furthermore, inasmuch as these two groups of springs 10 work in opposition to each other, they will necessarily tend to center the box and the yoke when the forces of draft are relaxed.

It will be seen from the foregoing that I have provided two groups of friction devices 15 for taking up and dissipating the forces of the recoil; one group of said devices comprising friction devices located inside of the housing, and the other group of said devices comprising friction devices located outside of the 20 housing.

Figs. 4 to 10, inclusive, illustrate modified constructions of the friction devices located outside of the housing.

In the construction of Fig. 4 the projecting 25 ends 41 and 42 of the pin 40 carry diamond-shaped blocks 61 which are embraced between companion abutment blocks 62 and 63, the latter being slidable within U-shaped brackets 64 and 65, respectively. Springs 66 tend 30 to force the blocks 62 and 63 against the diamond-shaped block 61, so that the back and forth movements of the draw bar must be accommodated by a separation of the blocks 62 and 63.

35 It will be noted that this construction tends to restore the draft devices to their central position irrespective of the groups of springs 59 and 60; and it will also be noted that for this reason the normal draft may to some extent, or else wholly, be taken up by the springs 66.

The construction shown in Fig. 5 is similar to that of Fig. 4, with the exception that the block 61 has been modified in form into an ellipsoid 67, and the blocks 62 and 63 have 45 also been modified in form, as shown at 68 and 69, respectively.

In the construction of Fig. 6 the block 67 has been still further modified to provide end 50 lugs or projections 70 and 71; and corresponding modification of the shapes of the blocks 72 and 73 has also been made.

In the construction of Fig. 7 the central block has been still further modified and elongated to establish wave friction surfaces on top and bottom, as shown in the block 74, and the blocks 72 and 73 have been correspondingly modified, as shown at 75 and 76.

The construction of Fig. 8 is similar to 60 that of Fig. 7 with the exception that the ends of the blocks 74 are engaged by compression springs 77 and 78 which serve to assist in taking up the forces of draft, and said springs also serve to center the parts in the restoring 65 movement.

In the construction of Fig. 9 the block 74 has been provided with end fingers 79 and 80, the bottom faces of which are wedge-shaped; and companion wedge fingers 80 and 81 are pivoted to the frame bar at the points 82 and 83, respectively. Springs 84 and 85 press the fingers 80 and 81 against the fingers 79 and 80, so that the tendency is to restore the draft mechanism to its central position and at the same time to impose an additional amount of friction mechanism into the movements of the device.

In the modified construction of Fig. 10 there is provided a socket block 86 on the frame bar, said socket block being provided 80 with a concave spherical-form socket to receive a spherical block 87 which is mounted on the end portion of the pin 40. Said block 87 is socketed as shown at 88, so that as the pin travels back and forth in the slot 89 the 85 block 87 may rock in the socket of the block 86. A spring 90 mounted on the end portion of the pin 40 forces the block 87 firmly into the socket of the block 86 so as to create a desired amount of friction at this point.

If desired, the friction surfaces between the plates 32 and 33 and the frame bars 12 and 13 may be longitudinally corrugated so as to increase the amount of friction and resistance against back and forth movement 95 without actually preventing such movement.

While I have herein shown and described only certain embodiments of the features of my present invention, still I do not intend to limit myself thereto except as I may do so in 100 the claims.

I claim:

1. The combination with the underframing of a car including the central longitudinally-extending parallel frame bars, of transverse 105 abutments secured to and extending between said frame bars and serving to define the front and rear ends of a draft device housing, a box slidably mounted within said housing for back and forth movement therein, 110 said box including movable side walls in proximity to the inner faces of the frame bars, springs within said box serving to force the side walls thereof into frictional engagement with the frame bars, the frame bars being 115 longitudinally slotted opposite to the position of said box, a transverse pin extending through the box and through said slots to the outsides of the frame bars, wedge blocks secured to the outsides of the frame bars at 120 the sides of said slots, companion wedge blocks on the end portions of said pin, springs serving to maintain the pin, wedge blocks in firm engagement with the side bar wedge blocks, springs between the ends of the box 125 and the abutments aforesaid tending to restore the box to the central position, and a suitable coupler in connection with the box and transmitting push and pull forces directly thereto, substantially as described. 130

2. The combination with the underframing of a car including the central longitudinally-extending parallel frame bars, of transverse abutments secured to and extending between said frame bars and serving to define the front and rear ends of a draft device housing, a box slidably mounted within said housing and between said abutments, springs between the ends of the box and the abutments tending to restore the box to the central position, the frame bars being longitudinally slotted at positions opposite to the box, a transverse pin extending through the box and through said slots, wedge blocks secured to the outside faces of the frame bars adjacent to said slots, companion wedge blocks on the projecting ends of the pin, spring means for maintaining said wedge blocks in co-operative engagement with each other, a coupler, and a suitable connection between said coupler and the box, substantially as described.

3. The combination with the underframing of a car including the central longitudinally-extending parallel frame bars, of transverse abutments secured to and extending between said frame bars and serving to define the front and rear ends of a draft device housing, a member slidably mounted within said housing between said abutments, springs between the ends of said member and the adjacent abutments, the frame bars being longitudinally slotted adjacent to the central position of said member, a transverse pin carried by said member and extending through said slots, wedge blocks in conjunction with the outside faces of the frame bars adjacent to the positions of said slots, other wedge blocks, connections between the central portions of said wedge blocks and the projecting ends of the pin, spring means for maintaining said wedge blocks in co-operative relationship with each other, a suitable coupling, and an operative connection between said coupling and the slidably mounted member within the housing, substantially as described.

4. The combination with the underframing of a car including the central longitudinally-extending parallel frame bars, of transverse abutments secured to and extending between said frame bars and serving to define the front and rear ends of a draft device housing, a box slidably mounted within said housing, said box including side plates movable towards the inner faces of the frame bars, spring means within the box tending to force said side plates against the frame bars, spring means between the ends of the box and the abutments tending to restore the box to the central position, there being longitudinally extending slots in the frame bars opposite to the position of the box, a transverse pin extending through the box and through the slots and projecting to the outside of the frame bars, co-operative friction wedge devices on

the outside faces of the frame bars and the ends of the pin, and spring means for retaining said blocks in co-operative relationship with each other, substantially as described.

5. The combination with the underframing of a car including the central longitudinally-extending parallel frame bars, of transverse abutments secured to and extending between said frame bars and serving to define the front and rear ends of a draft device housing, a coupler, a member within said housing connected to said coupler and traveling therewith, springs between the ends of said member and the abutments aforesaid, friction plates connected to said member, stationary companion friction plates in conjunction with frame bars, all of said friction plates having friction surfaces extending parallel to the direction of movement, springs tending to force the friction plates together with a constant amount of pressure, other friction plates connected to and traveling with said traveling member and coupler, other stationary friction plates in conjunction therewith, all of said friction plates having companion friction surfaces non-parallel to the direction of movement, and spring means for retaining said non-parallel surface friction plates in frictional contact, whereby the amount of frictional engagement of said surfaces with each other increases with the amount of movement, substantially as described.

6. The combination with the underframing of a car, including longitudinally-extending parallel frame bars, of a coupler, a housing connected to and travelling with said coupler, friction surfaces stationary with respect to the inner faces of the frame bars, friction devices carried by the housing and travelling therewith and in frictional contact with said stationary friction surfaces, all of said friction surfaces being substantially plane and lying in a direction parallel to the direction of buffing movement of the coupler and housing, spring means tending to maintain said housing friction devices in frictional contact with the stationary friction surfaces with a constant amount of force during the buffing movements, other friction devices carried by the housing and movable towards and from the axis of movement of the coupler and housing, other friction devices and surfaces thereon stationary with respect to the outer faces of the frame bars, and engaged by the friction devices carried by the housing and last named, said last named friction devices having friction surfaces which are non-parallel to the direction of movement of the coupler and housing, and spring means for forcing the said friction devices together, whereby as the coupler and housing move during the buffing movement said spring means are placed under added spring force to thereby increase the friction-

al engagement existing between said friction devices, substantially as described.

7. The combination with the underframing of a car, including longitudinally-extending parallel frame bars, of a coupler, two sets of friction surfaces stationary with respect to the frame bars, one of said friction surface sets being parallel to the direction of buffing movement of the coupler, and the other set of said surfaces being non-parallel to the direction of buffing movement of the coupler, a set of friction devices connected to and moving with the coupler and in engagement with the friction surfaces which are parallel to the direction of buffing movement of the coupler, spring means for placing and maintaining said friction devices in engagement with said friction surfaces, another set of friction devices connected to and moving with the coupler and in engagement with the friction surfaces which are non-parallel to the direction of buffing movement of the coupler, and spring means for placing and maintaining said friction devices in engagement with said friction surfaces, whereby during the buffing movement of the coupler the first named friction devices and friction surfaces are under constant spring force and frictional engagement, and whereby during the buffing movement of the coupler the second named friction devices and friction surfaces and under a variable amount of frictional engagement to thereby ensure a variable amount of total frictional engagement as the coupler moves during the buffing action, substantially as described.

8. The combination with the underframing of a car, including longitudinally-extending frame bars, of a coupler, two sets of friction surfaces stationary with respect to the frame bars, one of said friction surface sets being parallel to the direction of buffing movement of the coupler, and the other set of said surfaces being non-parallel to the direction of buffing movement of the coupler, said non-parallel surfaces being a variable distance from each other measured in the direction of buffing movement of the coupler, friction devices connected to and moving with the coupler and in engagement with the stationary friction surfaces aforesaid, and spring means for forcing the friction devices into engagement with the stationary friction surfaces, whereby during buffing movement of the coupler the friction devices which engage the parallel friction surfaces are under a constant amount of frictional engagement therewith, and whereby during said buffing movement of the coupler the friction devices which engage the non-parallel friction surfaces are under a variable amount of frictional engagement therewith, substantially as described.

9. The combination with a car frame and the coupler therefor, of means for buffing the

movements of the coupler, said means comprising two sets of stationary friction surfaces connected to the car frame, one of said sets of surfaces being parallel to the direction of buffing movement, and the other set of said surfaces being non-parallel to the direction of buffing movement and being spaced a variable distance from each other measured in the direction of buffing movement, friction devices connected to and moving with the coupler and in engagement with said stationary friction surfaces, and spring means for maintaining the friction devices in such engagement with the friction surfaces, whereby during the buffing movement of the coupler the parallel friction surfaces and the friction devices in engagement therewith are under a constant amount of friction engagement, and whereby during such movement the non-parallel friction surfaces and the friction devices in engagement therewith are under a variable amount of frictional engagement, substantially as described.
